MULTIPLEX CHANNEL REPEATER SYSTEM

Gilbert S. Vernam, Hackensack, N. J., assignor to
 Postal Telegraph-Cable Company (New York),
 New York, N. Y., a corporation of New York

Application December 20, 1940, Serial No. 370,933

16 Claims. (Cl. 178—52)

The present invention relates to multiplex telegraph systems, and particularly to a repeater for connecting a channel of one multiplex telegraph circuit with a channel of another such circuit, irrespective of the synchronous speed of the two circuits. Ordinarily the repeater of this invention will be utilized to receive signals from a channel of a multiplex terminal set and to repeat those signals to a channel of another multiplex terminal set. The two sets may be operating at the same or different speeds.

In prior systems of this general type the repeater included means for receiving signals from a multiplex circuit, means for temporarily storing those signals, and means for taking the signals from the storage means and applying them to the proper channel segments of the sending distributor of the second multiplex circuit. If the two circuits were operating at different speeds, as is customary, it was necessary to stop the rotary switch which served as the means for transferring the signals from the storage means to the sending distributor, and thereby to permit the rotary switch which served as the means for transferring the signals from the receiving distributor to the storage means to catch up. In the present invention it is unnecessary to stop the rotary switch on the sending side of the repeater, but instead means are provided for causing the rotary switch on the receiving side of the repeater to take two steps at certain times whereby it is prevented from lagging behind the sending switch.

In systems of this type it is necessary that the effective signal speed on the receiving side of the repeater be no greater than the speed on the sending side of the repeater. In order to assure this, means are provided to cause the transmitter at the distant end of the line and connected to the receiving side of the repeater to periodically send a blank or idle signal thereby reducing the effective signal speed on the receiving side to or below the speed of the sending side.

In a prior system for achieving this the means for reducing the effective transmitter speed included an electron discharge tube having a storage condenser in its grid circuit. This means, though operable, is relatively complicated and difficult to maintain. In the present invention a simple means for bringing about this same result is provided, this means comprising a rotary switch which is inserted in the transmitter actuating circuit and which is effective to periodically prevent operation of the transmitter dur-

ing a single cycle of the associated transmitting distributor to thereby cause an idle signal to be sent over the line to the receiving side of the channel repeater.

5 The present invention further contemplates an alarm circuit which will operate whenever the transmitter at the distant end of one line section is operating at a rate of speed which differs from the speed of operation of the second line section, to an extent greater than the signal storage capacity of the multiplex channel repeater.

In addition to the equipment briefly mentioned above, my present invention includes a circuit for monitoring the repeater. This circuit is so arranged that a monitoring printer may be inserted in the repeater circuit in such manner as to receive the signals directly from the multiplex receiving distributor or to receive the signals from the sending side of the repeater to determine whether the signals passing to the outgoing line are satisfactory. In addition the circuit is so arranged that signals may be originated from a transmitter included in the monitoring equipment, passed through the repeater, and received on a monitoring printer, thereby to determine whether or not the repeater is operating properly. Furthermore, this monitoring equipment may be utilized as a temporary communication circuit by connecting the monitor 20 transmitter to one of the line sections through the repeater and by connecting the monitoring printer to the same line section on the receiving side of the channel repeater operating to pass signals in the opposite direction.

35 It will be obvious that the channel repeater of this invention may be utilized also in connection with multiplex start-stop translator equipment, as for example such equipment as is disclosed in the Hallden Patent No. 2,196,069 of April 2, 40 1940.

45 It is an object of my invention to provide a multiplex channel repeater in which the proper relationship of the rotary switches or like means on the receiving and sending sides of the repeater is maintained through the use of a circuit which causes the rotary switches on the receiving side of the repeater to take a double step at intervals determined by the relative positions of the switches on the sending and receiving side.

50 It is another object of my invention to provide an alarm circuit which will operate whenever the speed difference between the received signals and the sending equipment exceeds the storage capacity of the repeater.

55 It is a further object of my invention to pro-

vide a simple and effective means for reducing the effective sending rate of a transmitter by periodically stopping the transmitter and causing it to send an idle or blank signal.

It is a still further object of my invention to provide a monitoring means whereby the operation of a multiplex channel repeater may be checked.

Other objects and features of the invention will appear when the annexed specification is considered in connection with the appended drawings, in which

Figures 1 and 2, taken together, form a circuit diagram of a multiplex channel repeater.

Figure 3 is a circuit diagram of a transmitter control mechanism adapted to reduce the effective speed of a multiplex transmitter.

Figure 4 is a chart showing the frequency with which the circuit of Figure 3 causes the multiplex transmitter to send blank or idle signals for each setting of the control switch of Figure 3.

Figure 5 is a schematic diagram of a circuit for monitoring the input and output of the repeater of Figures 1 and 2.

From the foregoing it will be apparent that the multiplex channel repeater of this invention receives from a receiving multiplex distributor the five signal impulses constituting one character in the five unit code and stores those impulses for a fraction of a second, and at the proper instant releases those impulses to a sending multiplex distributor. The signals sent out from the repeater usually lag two or three characters behind the signals received by the repeater, and therefore the repeater is designed to store a maximum of five characters.

Signals from the multiplex "printer relay," through the multiplex receiving distributor, operate the receiving-selecting relays 16 through 20 (Fig. 1). These relays correspond to the selecting magnets of a multiplex printer and operate in a similar manner. The signals are then transferred from these relays through a step-by-step rotary switch 30 to a group of five condensers, this group comprising one condenser from each of the groups 42 through 46.

There are five groups of condensers 42 through 46, as mentioned above, which are switched into the circuit successively so that five complete character signals can be stored before the condensers must be re-used. The stored signals are transferred successively from the condensers through a second step-by-step rotary switch 50 to the five sending selecting relays 76 through 80 (Fig. 2). The contacts of these relays correspond to the contacts of a multiplex tape transmitter and control the transmission of the signals through the sending distributor to the second line section.

The receiving rotary switch 30 steps its wipers one step for each revolution of the receiving distributor and in like fashion the sending rotary switch 50 steps its wipers one step for each revolution of the sending distributor. Since the distributors run at different speeds, it would be obvious that the switches would step at different rates. For proper operation of the repeater, however, the sending switch 50 must always lag at least one step behind the receiving switch 30, and as there are but five sets of storing condensers 42 through 46, it is obvious that the sending switch must not be allowed to lag as much as five steps behind the receiving switch.

If the repeater is operating from "slow" to "fast," that is, repeating signals from the slower

receiving distributor to a faster sending distributor, the sending rotary switch 50 will tend to gain on the receiving rotary switch 30. To prevent the sending switch from catching up to 5 and passing the receiving switch, the circuits are so arranged that whenever the wipers of the sending switch are but one step behind those of the receiving switch, the receiving switch is, on its next operation, caused to take two steps. This double stepping action is controlled by a control relay which will later be described.

When such double stepping occurs, one set of storing condensers is passed over without being charged, thereby causing the sending relays 15 to transmit an idle signal. As a result of this action the repeater automatically introduces sufficient idle signals or "blanks" in the train of outgoing signals to compensate for the difference in speeds of the two distributors, the receiving rotary switch always taking exactly the same total number of steps as the sending rotary switch despite a speed difference between the receiving and sending distributors.

When character signals from the remote transmitting station stop, idle signals, that is, signals having no selecting impulse, are received at the repeater thus causing the receiving rotary switch 30 to stop. Under these circumstances the sending switch continues to step until all 30 signals stored in the condensers have been transmitted and then it too stops, being at this time one step behind the receiving switch.

If the repeater is operating from "fast" to "slow," or in other words if the receiving distributor is running faster than the sending distributor, the receiving switch 30 will, of course, tend to gain on the sending switch 50 but due to the fact that idle signals are received at regular intervals from the remote transmitting station due to the use at that station of the transmitter control unit shown in Figure 3, and subsequently to be described, the receiving switch wipers will stop periodically in order to allow the sending switch wipers to catch up. While the wipers are stopped the condensers are not charged, and thus the next character signal is received and stored on the group of condensers immediately following that on which the preceding character signal is stored, thereby dropping out the idle signals and compensating for the speed difference.

Since it is not possible with the transmitter control circuit of Figure 3 to match the effective signal speed of the signals on the first line section exactly to the signal speed of the sending distributor from the second line section, the transmitter control circuit will stop the transmitter slightly more often than is necessary. As a result of this the sending switch 50 will occasionally approach within one step of the receiving switch 30 and cause the receiving switch to double step. This will always occur immediately after the receiving switch has stopped as this is the only time that the sending switch can catch up to it. Occasionally idle signals will therefore be transmitted from the repeater but they will be fewer than the number received.

For example, if we assume that the first line section is operating at 60 words per minute, and a channel thereof is connected through the channel repeater to a channel of a second line section operating at 52 words per minute, then the transmitter control circuit at the distant end of the first line section would be set to stop the transmitter after every fifth character thus

reducing the effective character signal speed to five-sixths of 60 or 50 words per minute. Most of the idle signals transmitted from the sending station will be dropped out at the repeater as explained above, but one will be transmitted after every 25 characters to increase the speed from 50 to 52 words per minute.

If the repeater is receiving signals from a channel operating at a higher speed than the channel into which the repeater is sending, and if the average received signal speed is not sufficiently reduced by the transmitter control circuit, signals will accumulate at the repeater and errors will result, since under these conditions the receiving rotary switch will gain continuously and its wipers will pass the terminals that are connected at the moment to the sending switch wipers. In order to warn of this condition an off speed alarm has been provided which is controlled by a relay and which will be described subsequently.

As has been indicated above, two repeaters are always required, one for repeating signals in one direction and one for repeating signals in the opposite direction. These two repeaters are so interconnected that when the transmitter locking switch on one multiplex set is operated, the sending relays of the repeater which is sending into that set will be released to send idle signals, while the other repeater will send "letter" signals back over the other line to serve as a stop signal. The reception of "letter" signals notifies the operator not to send on this channel as it is out of service beyond the repeater. During times when the multiplex circuits are being synchronized and phased preparatory to being put into service, idle signals will be sent out by both repeaters, certain control relays being provided for this purpose as will later appear.

Operating circuit—receiving selecting relays

Relays 16 through 20 inclusive are connected to the receiving segments 11 through 15 respectively of the particular channel of the receiving distributor, and are operated in accordance with the code signals received by the printer relay 16 as the distributor brush passes over the segments associated with the channel. Each of the relays 16 through 20 has a primary or operating winding and a secondary or locking winding. It is only necessary for a short impulse from the distributor segment to close contacts A of one of these relays and then current flowing from battery through the locking winding of that relay to ground at contacts C of control relay 23 to completely operate the relay and close the remaining contacts thereof. It will be obvious that the receiving selecting relays 16 through 20 operate in accordance with the code combination received. For example, when the letter *a* is received, relays 16 and 17 will operate and lock, while when the letter *b* is received, relays 16, 19 and 20 will operate and lock, and so on in accordance with the well known five unit printer code.

After the selecting impulses have been received, and selected ones of the relays 16 through 20 operated as described above, the sixth pulse contacts 24 will close at a time determined by the sixth pulse cam 22. Closure of the sixth pulse contacts 24 will complete a circuit leading through contacts B of receiving selecting relays 16 through 20, and through the operating winding of control relay 25 to ground. Due to the

fact that the circuit for control relay 25 extends through contacts B of all five selecting relays in parallel, it will be obvious that at least one of these selecting relays must have operated before relay 25 can operate. It is thus apparent that when idle signals are received relay 25 does not operate and the receiving side of the repeater remains inoperative.

The secondary winding of relay 25 is short-circuited at its contacts D when the relay is operated. When at the termination of the sixth pulse the circuit to the primary winding of relay 25 is opened at the sixth pulse contacts 24 a current is induced in the secondary winding which holds the relay operated for a fraction of a second. This, in effect, increases the length of the sixth pulse and insures proper operation of the stepping magnet 28 of rotary switch 30 even when distributors having a short sixth pulse are used.

Relay 25 operates relay 23 which, in turn, releases the receiving selecting relays 16 through 20 by opening their locking circuits at contact C. Relays 25 and 23 must, however, both release before the distributor brush completes its revolution so that relay 16 will be properly locked if it should be operated by the next character signal.

30

Charging the storing condensers

While operating selecting relays remain operated, the sixth pulse relay 25 operates and applies battery through its contacts E and through contacts C of the operated selecting relays and wipers of rotary switch 30, to charge a group of five condensers comprising one condenser from each of the groups 42 through 46. This charging action takes place very soon after relay 25 operates, and the condensers are completely charged before the selecting relays 16 through 20 release.

Stepping the receiving rotary switch

45 Sixth pulse control relay 25 operates the stepping magnet 28 of the rotary switch 30. When the magnet 28 operates, its contacts C remove a short-circuit from a resistance 31, and thus include that resistance in the circuit of the magnet winding. This arrangement provides a strong current for operating the magnet 28 quickly, but reduces the current by causing it to flow through resistances 27 to 31 in series when the magnet has operated, thereby saving current and preventing overheating of the magnet in case the receiving distributor should be stopped and left with the sixth pulse contacts 24 closed.

50 Magnet 28 advances the ordinary pawl and ratchet mechanism of stepping switch 30 to its next tooth, and when relay 25 releases magnet 28 also releases and steps the wipers of the switch ahead one step, thereby connecting the relays 16 through 20, respectively, to another group of five condensers comprising one condenser from each of the groups 42 through 46, leaving the first character signal stored on the first set of condensers.

55 The same operations as described above are repeated for each revolution of the receiving distributor until five successive character signals 60 have been stored in the condensers 42 through 46. The sixth received character is stored on the same condensers as the first received character but, of course, these condensers will have in the meantime been discharged through the send-

75

ing relays. These operations continue as long as message signals are received.

Stepping the sending rotary switch and operating the sending-selecting relays

As has been indicated above, there are provided five sending-selecting relays 76 through 80, each of these relays having an armature which is connected to a corresponding one of the segments 91 through 95 of a sending multiplex distributor, the cooperating contacts C and D of these relays being connected to battery (see Fig. 2), the contacts of the fifth pulse relay 80 being reversed in the same manner as is customary in connection with the fifth contacts of the multiplex tape transmitter, and for the purpose of transmitting signal reversals when the distributor is running idle. The operating windings of relays 76 through 80 are connected through the wipers of the sending rotary switch 50 to the same condensers as store the received impulses. The sending sixth pulse control relay 81, by closing its contacts B, operates the stepping magnet 88 of the sending rotary switch 50. Thus relay 81, by opening its contacts A also releases any of the sending-selecting relays 76 through 80 which has been previously operated. When relay 81 releases, the magnet 88 also releases, and steps the switch wipers of switch 50 ahead to thereby connect the sending-selecting relays to the next group of condensers. Those condensers of the group which were previously charged under control of the receiving-selecting relays now discharge through corresponding ones of relays 76 through 80 operating those relays which correspond to selecting impulses in the stored signal. Operated ones of these relays lock in their operated position due to completion of the circuit through contacts A of these relays and contacts A of relay 81.

The character signal set up on the contacts of relays 76 through 80 is transmitted by the sending multiplex distributor, after which relay 81 again operates due to completion of the sixth pulse circuit through sixth pulse contacts 82 of the winding of relay 81. Thus operation of relay 81 serves, as described above, to release the selecting relays and to cause the rotary switch to step, select and discharge the next group of condensers into the selecting relays. These operations continue as long as there are any stored signals to be transmitted.

Double stepping circuit

The foregoing has explained how character signals are received from one channel of the receiving multiplex distributor on the receiving relays 16 through 20, transferred through receiving rotary switch 30, to condensers of the five groups 42 through 46, and then again transferred from the condensers through the sending rotary switch 50 to sending relays 76 through 80 from which the signals are sent out through a channel of a sending multiplex distributor to the second line section. From this description it is obvious that even though the two distributors may run at different speeds the sending rotary switch must always be not less than one, nor more than four steps behind the receiving switch. As indicated, in order to maintain this relation when the repeater is repeating from a faster to a slower channel, the receiving switch is stopped periodically by transmitting idle signals from the sending station. This stopping action drops out the

idle signals and tends to make the receiving switch take fewer steps than the sending switch, as in the case when repeating from a slower to a faster channel. To equalize the total number of steps taken by the two switches, and to prevent the sending switch from overtaking and passing the receiving switch, the latter switch is caused to "double step" at times under control of the circuit now to be described.

10 Each of the rotary switches 30 and 50 is provided with a sixth bank of contacts designated, respectively, 41 and 61, contacts of bank 41 being connected to those of bank 61 as follows: The first contact of bank 41 to the fifth contact of bank 61; the second contact of bank 41 to the first contact of bank 61; and so on, in other words each bank contact of the sending switch being connected to the next bank contact ahead on the receiving switch. As a result of this 15 method of connection the wiper of the sixth bank of contacts 61 of the sending switch is connected to the wiper of the sixth bank of contacts 41 of the receiving switch only when the sending switch is one step behind the receiving switch. 20 When it occurs that the sending switch is but one step behind the receiving switch, battery is connected through resistance 32 and conductor 33 to the wiper of bank 61 of switch 50, and thence to the wiper of switch bank 41 of switch 30, and through conductor 34 to the upper armature of relay 23. When, thereafter, the receiving distributor sixth pulse causes relays 25 and 23 to operate, relay 25 operates magnet 28 as previously described and at the same time relay 23 causes 35 operation of relay 35 due to the completion of the circuit just previously described from the upper armature of relay 23, to contact B of that relay and through the winding of relay 35 to ground. When relay 25 releases, magnet 28 also 40 releases and steps the receiving switch wipers ahead one step in the same manner as has been previously described. When magnet 28 releases, however, a circuit is completed through resistance 32 and conductors 33 and 42, contact A and upper armature of magnet 28, conductor 43, contact A and upper armature of relay 35, and the winding of relay 35 to ground. This locking circuit retains relay 35 operated.

50 Relay 23 is slightly slow to release, as has been mentioned hereinabove, so that it does not release until after magnet 28 has released. When the relay 23 releases it closes a circuit through its contacts D and contacts B of relay 35 to the winding of stepping magnet 28 which causes 55 magnet 28 to operate again. Upon such operation the locking circuit for relay 35 is opened at contact A of stepping magnet 28 and thus relay 35 releases and, in turn releases stepping magnet 28 causing switch wipers of switch 30 to take a 60 second step.

When the receiving rotary switch wipers take a double step as just described, in order to keep ahead of the sending switch wipers, the receiving switch wipers pass over contacts of the banks 65 36 through 40 connected to one group of five condensers. These five condensers are not charged at this time due to the fact that the relays 16 through 20 are not operated when the second stepping action occurs. This results in 70 effect in storing idle signals on one group of condensers. Thus when the sending switch wipers of the banks 56 through 60 make connection to this group of condensers, no one of the relays 76 through 80 will be operated and consequently 75 an idle signal will be transmitted to the second

line section during the next revolution of the sending distributor.

Stopping the rotary switch when idle

When signals from the transmitting station stop completely, the five receiving-selecting relays 16 through 20 remain unoperated, and since as has been described sixth pulse control relay 25 is operated through the parallel connected contacts of these selecting relays, relay 25 does not operate. Due to the non-operation of this relay the receiving rotary switch stops.

The sending switch, however, continues to operate until the wipers are one step behind those of the receiving switch, when a circuit previously described is closed through the wipers of the sixth contact banks 41 and 61 of the receiving and sending switches to the upper armature of relay 23. Due to the fact that relay 23 is not operated, this circuit is extended through contact A of this relay and conductor 44 to the winding of relay 96 and thence to ground. Relay 96 (Fig. 2) is thus caused to operate and in so doing opens the circuit to the sending stepping switch 88 (Fig. 1) at its contacts B, stopping the sending switch. The last character signal stored on the condensers will have been transferred to the sending relays on the last step of the sending switch. Relay 81 will continue to operate, assuring the final release of relays 76 through 80 after the transmission of the last character signal. However, due to the operation of relay 96 the continued operation of relay 81 will be ineffective to cause stepping of the rotary switch.

Re-starting

When character signals (i. e. signals other than idle signals) are again received, relays 16 through 20 (Fig. 1) will again operate, closing the circuit for relay 25. Since the sending switch is only one step behind the receiving switch at this time, relays 23 and 35 operate when the first character signal is received and the receiving switch 30 takes a double step after which it continues to operate in the normal manner. This double stepping action always takes place after the circuit has been idle, thus introducing an idle signal after the first character signal transmitted from the repeater. When relay 23 operates it releases the relay 96 so that the stepping action of the sending switch 50 starts immediately after the stepping action of the receiving switch 30.

Indicating lamp

An indicating lamp is provided to show when the repeater is operating normally, and when idle signals are being received by and passed through the repeater. This lamp is shown in Figure 1 and designated 101. The lamp is in a circuit which leads from battery through resistances 32 and 102, over conductor 103 to the lamp 101, and thence over conductors 104 to 105 to ground. Thus when the repeater is operating normally, the lamp is lighted except, however, that each time that the receiving switch 30 double steps, the winding of relay 35 is shunted across the lamp causing it to be extinguished momentarily. Thus in normal operation the lamp will light steadily except that it will blink occasionally at uniform intervals. However, when the circuit is idle and relay 96 is operated, as has been described above, the winding of this relay is shunted across the lamp and therefore the lamp is extinguished, such a steady state indicating

that the repeater is receiving idle signals only. Thus the signal lamp mentioned serves to indicate whether the repeater is idle or operating in a normal manner.

5

Off speed alarm signal

As has been stated hereinabove, a condition is possible wherein signals are received at a rate sufficiently in excess of the transmitting speed 10 so that the storage capacity of the repeater is exceeded. A lamp is provided to indicate when this condition exists, the lamp being shown in Figure 1 and being designated 106. The circuit which controls this signal involves both the receiving and the sending relays. When the off-speed alarm toggle switch 107 (Fig. 1) is closed, a circuit is completed from battery through resistance 108, lower winding of electro-polar relay 109, conductor 110, the upper blade of switch 107, and conductors 104 and 105 to ground. The construction of the so-called electro-polar relay 109 is such that it has substantially the same characteristics as a polar relay and is operable on a very short current impulse. This relay has an iron collar around the center portion of its core which is connected to an outer pole piece or back-stop in front of the armature. Current flowing through the winding due to closure of the circuit previously described magnetizes the outer pole piece as well as the core, and since the armature is between the pole piece and the core end it is not pulled strongly in either direction and the pressure of the contact springs will normally hold it in the released position. If 25 while this winding is energized a short current impulse is sent through the other or operating winding, it will increase the pull due to the core and the armature will pull up, but since the armature is closer to the core than to the outer pole piece, it will remain operated even though the current impulse through the operating winding ceases until the magnetizing winding is opened by opening the toggle switch 107.

The receiving selecting relays 16 to 20 normally release immediately after relay 23 operates, as has been described, but when the toggle switch 107 is closed, a ground is connected through conductors 105, 104, lower blade of toggle switch 107, conductor 111, resistance 112, contact C of relay 25, conductor 22, contacts A of relays 16 through 20, and the windings of those relays, to battery. Thus the receiving-selecting relays are held operated until relay 25 releases. However, the resistance 112 so reduces the strength of the locking current that the receiving-selecting relays 16 through 20 will release quickly upon the release of relay 25. This release time is so small that the relays 16 through 20 will be released before relay 23 can release to re-close their locking circuits. There is, therefore, a brief interval after relay 25 releases when battery is connected through the upper or operating winding of electro-polar relay 109, the circuit therefor being as follows: From battery through conductor 113, the operating winding of relay 109, lower armature and contact E of relay 23, conductor 114, and through contacts C and cooperating armatures of any relay or relays of the group 16 through 20 which have been operated to the wipers of the receiving rotary switch 30 and thence to particular ones of the groups of condensers 42 through 46, the condensers of the group being dependent, of course, upon the position of the wipers of switch 70 30.

Since the condensers charge very quickly when relay 25 first operates, they will be completely charged when the release of relay 25 removes the short-circuit from the operating winding of relay 109. Since these condensers are completely charged, no current will flow through the operating winding of relay 109 and during the normal operation of the repeater relay 109 will not operate. If, however, the condition mentioned above, that is, the condition of excess character signal speed occurs, the receiving rotary switch will not stop sufficiently often with the result that the wipers of receiving rotary switch 30 will overtake the wipers of sending rotary switch 56. When this occurs contacts C of the receiving relay 16 through 20 will be connected directly through the wipers of the corresponding banks of the receiving switch 30 and the wipers of the similarly corresponding banks of the sending rotary switch 56, to the windings of sending relay 16 through 20, respectively.

Thus the circuit described above, through the operating winding of relay 109, will be completed and current will continue to flow operating relay 109 at the time when relay 25 releases. Relay 109 will close a circuit at its contacts A leading through conductor 115 to signal lamp 116 and thence over conductors 104 and 105 to ground. The lamp will, of course, remain lighted until relay 109 is released, by opening the toggle switch 107.

In addition, operation of relay 109 will close a circuit leading from battery through bell 117, conductor 118 and contacts B of relay 109 to ground. This will bring about operation of the multi-bell 117, which bell is common to all the multiplex channel repeaters in an office and operates whenever any one of these repeaters is "off speed." Of course the bell ceases to operate when the toggle switch 107 of the repeater which is "off speed" is opened.

Stop signal

It is necessary when the multiplex terminal sets of one line section are being synchronized, or a line section is out of service for any other reason, to send a "stop" signal from the repeater over the other line section in order to notify the operator not to send over the through channel, although of course operation of the non-repeated channel of the terminal sets on the second line section may be continued. The "letters" signal is utilized as a stop signal since it can be easily recognized and does not cause the printer to record characters repeatedly. When channel repeaters of the type herein disclosed are used, there is no connection between the two line sections except that through the repeaters. Therefore the repeaters themselves must be arranged to transmit this signal when required. As indicated, the sending of this "letters" stop signal involves the sending sides of the two channel repeaters operating to repeat signals in opposite directions from one line section to the other.

Referring now to Figure 2, the stop signal circuit will be described, it being understood that the single sending side will be utilized as an illustration, the circuits being through it, and (by referring to it) through the sending side of the associated repeater.

Under normal operating conditions relays 81 of the two repeaters are continually operated by impulses from the corresponding sixth pulse contacts 82. These contacts are closed and the re-

lays consequently operated for a short period during each revolution of the distributors, but are released during the remainder of each revolution. The slow to release relays 84 are operated through contacts E of relays 81 and therefore current flows through their windings most of the time. When the windings of these relays 84 are opened, the relays nevertheless remain operated due to their slow to release characteristics, but will release in about one-half second. Thus if the relays 81 be operated for a time greater than one-half second, the relays 84 will release. Relays 81 may be held open by operating the transmitter locking switch 83 to close contacts A thereof.

When the transmitter switch 83 associated with one repeater is operated relay 84 of that repeater will release after the half-second interval mentioned, and a circuit will then be completed leading from ground through contacts B of relay 84, and over conductor 128, to contacts A of relay 84 of the other repeater of the pair, and thence through relay 121 (Fig. 2) to battery. This will cause relay 121 of the second repeater to operate and the operation of this relay will connect spacing battery directly through its contact to the first four transmitting segments 91 through 94 and marking battery to the fifth segment 95, thereby sending the letters signal repeatedly to the distant terminal, to advise the operator thereat of a failure in the other or first line section.

The release of relay 84 of the first repeater of the pair, as described, will also apply ground to conductor 122, thus short-circuiting the operating winding of relay 25 (Fig. 1), thereby stopping the rotary switch 30 of the first repeater and transmitting idle signals from this repeater over the first line section. Of course if the transmitter locking switch 83 of the other repeater, that is, the second repeater, had been operated, then the letter signals would have been sent back over the first line section and the idle signal would have been sent out from the repeater on the second line section.

If the locking switches 83 of both associated repeaters had been operated, then relay 84 of both repeaters would have been released and therefore neither of the relays 121 would be operated. In this manner idle signals would be transmitted from the repeaters over both line sections. This condition would obtain, for example, if both circuits were being "lined up," that is, synchronized and phased.

Transmitter control mechanism

As has been stated above, when a channel repeater is in service it is necessary that the effective signal speed of transmission from the distant station be reduced to a point at least as low as, and preferably lower than the speed at which signals are being transmitted over the line section into which the repeater sends its signals. For this purpose the circuit and mechanism shown in full lines at the right of Figure 3 is supplied. This circuit operates in conjunction with the usual transmitter and "auto speed" control shown in dash lines at the left of Figure 3. In order that the operation of the speed reducing unit be clear, the normal mode of operation of the transmitter and "auto stop" unit will first be briefly described.

When the sixth pulse contacts of the transmitting distributor close, circuits are completed through these contacts from battery to the transmitter operating magnets 131, to relay 132, and through contacts 133 controlled by the tape lever

134 to relay 135. This results in operation of the transmitter magnets and of relays 132 and 135. A circuit which would otherwise be completed at contacts A of relay 132 to cause operation of the transmitter locking magnets 136, is broken at contacts A of relay 135 and therefore the only effective operation is that of the operating magnets 131.

The transmitter continues to step as the sixth pulse contacts 130 are closed until such time as the perforated tape, normally extending in a loop below the tape lever 134, becomes taut, at which time contacts 133 are opened and the next sixth pulse operates only relays 132 and transmitter operating magnets 131, leaving relay 135 deenergized.

As a result of this the circuit is completed through contacts A of relay 132 and transmitter locking magnets 136. This causes the operating magnets as well as the locking magnets to be energized, and locks the transmitter so that no further operation can occur. When the tape lever 134 is restored to its normal position, the next following closure of the sixth pulse contacts 130 will again energize relay 135 and break the locking circuit to the operating magnets 136 thereby permitting the transmitter to resume normal operation.

In adapting this transmitter for use in conjunction with the speed reducing unit, a jack 137 is inserted in the circuit to relay 135. Normally the circuit is closed through the jack due to completion of the circuit through the tip and cooperating make contacts of the jack. However when the plug 138 is inserted in the jack 137 this circuit is broken and instead the circuit from the tape lever contacts 133 leads through the sleeve of jack 137 to the sleeve of plug 138 and thence over conductors 140 and 141 to the lower rotor of a commutator type switch 150, and when the switch is in any position other than its off position, through that rotor and conductor 142 and through the lower winding of relay 143 and conductor 144, and through plug and socket connection 145 to ground.

In addition the circuit extends over conductor 141 to a number of contacts of the rotary switch 151. Among these contacts is the first one on which the switch wiper is resting in the position shown in the drawings. For this position, therefore, the circuit is extended through the switch wiper to conductor 146 and through the tip of plug 138 and tip of jack 137 to relay 135. Thus the relay 135 will receive an impulse from the sixth pulse contacts 130 and the transmitter and auto stop unit will operate in normal manner. In addition, relay 143 will receive an impulse and will operate, and once operated will be locked in operated position over a circuit extending from battery through plug connection 145 and over conductors 147 and 148, resistance 152, to contacts A of the stepping magnet 153 of rotary switch 151, thence through the winding of stepping magnet 153 to conductor 154, and through closed contact B of relay 143 to conductor 144 and ground. Operation of relay 143 in addition causes closure of a locking circuit for that relay, which circuit may be traced as follows: from battery through the plug connection 145, conductors 147 and 155, resistance 156, upper winding of relay 143, and contacts A of that relay, and thence over conductor 157 to contacts B of stepping magnet 153, and by way of conductors 158 and 144 to ground.

Due to the circuits just described, relay 143

locks in its operated position and thus assures complete operation of stepping magnet 153, the circuit through locking winding of relay 143 being broken at contacts B of stepping magnet 153 when that magnet has completed its operation.

5 When that magnet has completed its operation. Thus even though the sixth pulse be extremely short, the operation of stepping switch 151 is assured. Contacts A are supplied for stepping magnet 153 so that though the operating current 10 for that magnet passes through resistance 152 only, and is therefore fairly great, holding current for the magnet passes through resistance 152 and resistance 160 and is therefore of lesser value.

15 Each time that the sixth pulse contacts are closed, stepping switch 151 is advanced one step. As shown in the drawings, with the control handle set to its eighth position, during the first two steps of movement the tape transmitter will operate in normal fashion and the tape therein will be advanced two steps and two character signals sent from the transmitter to the sending transmitter and to the line. When the wiper rests on its third contact, however, it will be noted that no circuit is completed through any of the commutators of switch 150 or otherwise to relay 135, and consequently the transmitter is locked until succeeding closure of the sixth pulse contacts 130. However the wiper of the rotary switch 151 steps to its fourth position and thus when the next closure of the sixth pulse contacts 130 occurs a circuit is completed leading from battery through these contacts over sleeve of jack 137 and sleeve of plug 138 and conductors 140 and 141 to the commutator second from the top in Figure 3, to conductor 161, and thence to the fourth contact of rotary switch 151, thence to the wiper of that switch and over a circuit previously described, to relay 135.

40 As has been described, this releases the locking magnets 136 and permits the transmitter to step the tape ahead a single step. Without tracing the circuits in any greater detail, it will be obvious that the transmitter is locked and caused to send blank or idle signals at certain periods dependent upon the setting of the commutators of switch 150, which commutators are mounted on a common shaft and controlled by the knob, shown, together with its cooperating scale at 162. By reference to the chart of Figure 4 it

45 will be seen that when the switch is in its eighth position as shown, eight of every twenty-four signals sent from the transmitter are blanks, these being as follows: third, sixth, ninth, twelfth, fifteenth, eighteenth, twenty-first and twenty-fourth. By comparing the connections of the commutator switch 150 of Fig. 3 with the chart, Fig. 4, it will be obvious that the various commutators are so laid out and the connections so made that for each position of the switch the transmitter is caused to send a different number of blank signals in each group of twenty-four signals. Thus it is shown by the chart that when the switch is set at seventh position, seven blank signals are present in each twenty-four signals transmitted, and when in the sixth position six blank signals are transmitted for each twenty-four signals.

50 When the switch handle 162 is rotated to its "off" position, the fifth commutator of the switch (counting from the top Fig. 3) is so positioned that a circuit is extended from conductor 141 to conductor 146, thereby causing the transmitter and autopilot unit to operate in the same fashion as if no speed reduction unit were used. This is

done merely for convenience and so that it is unnecessary to remove plug 138 from jack 137. Also at this time the circuit to operating winding of relay 143 is broken at the lowermost commutator of switch 150, thereby preventing operation of relay 143 or of the stepping switch 151, the speed reduction unit being completely idle when the switch is in the "off" position.

Monitoring arrangements

In the foregoing, mention has been made of the monitoring arrangements which provided means not only for checking the operation of the repeater, but also for "talking" from the repeater to the distant terminal station. This monitoring equipment consists of a tape transmitter and auto-stop unit identical to the one just previously described in connection with the speed reduction unit, together with a test distributor, that is, a distributor having both sending and receiving segments and well known in the art. In addition the monitoring equipment includes a multiplex printer and a multi-contact switch for rearranging the circuits in five different manners, as will be described.

In the drawing, Figure 5, the transmitter and auto-stop unit are enclosed in dotted lines and are designated 170, the unit being supplied with a jack exactly similar as respects circuit arrangements with the jack 137 of Figure 3. The five sending segments of the test distributor are indicated at 171 and are connected to the contacts of transmitter 170. These contacts are in turn strapped together and to the two leads 172 and 173, each of which connects to one of the windings of the differential polar relay 174, after which the two circuits join and are grounded. Relay 174 corresponds to the printer relay of an ordinary multiplex terminal set. The single armature of this relay 174 is grounded and the contacts thereof are connected to the receiving segments 175 of the test distributor, the contact A being connected to the first four of these segments and contacts B to the fifth segment, in order to provide for signal reversals during transmission of idle signals, as has been mentioned hereinabove.

The multiplex printer mentioned above is indicated in the drawing (Fig. 5) by showing the five magnets thereof designated 176 in the drawing. In addition to the equipment already mentioned, there are provided two plugs 177 and 180, plug 177 being adapted for insertion in the corresponding plug receptacle 178 on the output side of the repeater (see Fig. 2), and plug 180 being adapted for insertion in the corresponding plug receptacle 181 on the input side of the repeater (see Fig. 1).

When the switch 182 which comprises a plurality of contact arms settable in unison to any one of five positions is in its third position, as shown in Figure 5, circuits are completed which serve to test the transmitter 170. This arrangement is a common one provided in large telegraph offices so that transmitters and printers may be tested. Briefly when the switches are in this third position signals are sent from the transmitter contacts and received on the polar relay 174, these signals being then transferred to the receiving contacts and thence over conductors 183 through 187 on the first five banks of switch 182 to the five selecting magnets of the printer, and thence to battery and ground. The sixth pulse is supplied to the printer through a circuit extending through the sixth pulse seg-

5 ments of the receiving distributor and thence over conductor 188 to the sixth pulse magnet of the printer. It will be seen that these circuits are entirely local and that therefore the operation of the various units involved in the system may be tested by simply feeding a test tape through the transmitter.

If it is desired to check on the signals received by the repeater, switch 182 is set so that its switch arms rest on the first contacts. In this case a number of circuits is completed which may be traced as follows: From segment 11 of the receiving distributor, over conductor 190 to a terminal of plug receptacle 181 (Fig. 1), and thence to the corresponding terminal pin of plug 183 to conductor 191 through contacts A of relay 200, to conductor 192 and thence to the first selecting magnet of the printer, and to battery and ground. It may be seen that with such an arrangement the first printer magnet 176 operates in parallel with the first receiving selecting relay 16 (Fig. 1). The remaining printer selecting magnets 176 are connected in parallel with the remaining receiving selecting relays 17 through 20 in the same manner so that the first pulse selecting relay operates in parallel with the first pulse selecting magnet of the printer, the second pulse selecting relay operates in parallel with the second pulse printer magnet, etc. The sixth pulse control magnet 25 of the channel repeater (see Fig. 1) is provided with contacts A which contacts are connected through the plug receptacle 181 to conductor 193 (Fig. 5), to the winding of relay 200, and thence through the sixth switch bank and corresponding wiper arm to the sixth pulse magnet 176 of the printer.

40 Thus upon operation of the sixth pulse control relay 25, relay 200 is operated and breaks the circuit through its contacts A, B, C, D and E, leading from the distributor segments to the printer magnets. This relay 200 is supplied in order to prevent the printer magnets 176 from acting as high inductance shunts on the receiving selecting relays 16 through 20, and thus to assure that these relays do not have a slow to release characteristic while the monitor printer is in use.

45 It will be seen that due to the circuits just described the monitor printer is operated in parallel with the receiving selecting relays and thus the received signals are printed by the monitor printer as a check upon line conditions including of course the synchronization and phasing of the terminal multiplex distributors.

50 When the arms of switch 182 are set to their second position, the monitor set of Figure 5 is adapted to check the outgoing signals from the channel repeater. In this instance a typical one of the selecting magnet circuits, i. e. the circuit for the first printer magnet, can be traced as follows: From battery through the first magnet 176, thence through the first upper wiper arm and cooperating second contact of switch 182, to conductor 184, thence through plug 177 and receptacle 178 to conductor 195 (Fig. 2), thence through contacts B of relay 16, and contacts D of sending sixth pulse relay 81, to ground. Since the other selecting magnets 176 of the printer are connected in similar fashion to contacts B of the remaining sending selecting relays 17 through 20, it will be apparent that signals emanating from these relays are transmitted to the printer selecting magnets to properly set the printer for printing the corresponding character.

55 70 75 The sixth pulse for the printer is supplied over

the following circuit: from battery through sixth pulse magnet 176, thence over the wiper and second contact of the sixth contact bank of switch 182, and thence over conductors 196 and 197 through the plug and plug receptacle 177 and 178, over conductor 198 (Fig. 2) to contacts B of the stepping magnet 88 of the sending rotary switch 50 (Fig. 1). Thus upon each step of the sending rotary switch the monitor printer receives a sixth pulse and prints the same character which is being sent to the line through contacts C and D of the sending-selecting relays 76 through 80. When arranged in this fashion the monitor set gives a check on the outgoing signals from the repeater.

When the switch 182 is set with its wiper arms on the third contacts of the various switch banks, the monitor set is adapted for local testing of transmitters, printer, etc., as has already been mentioned.

When switch 182 is set with its wiper arms on its fourth contacts the circuit is arranged for "talking" with a distant terminal. When so used the plug 177 is inserted in the receptacle 178 of the channel repeater which is repeating signals in one direction between the two line sections, while the plug 180 is inserted in the receptacle 181 of the repeater operating to repeat signals in the opposite direction between the two line sections.

With the understanding that the plugs are inserted as described above, it will be seen that signals from the transmitter 170 are sent through the test distributor over conductors 183 through 187, and through the wiper arms of the first five of the lower contact banks of switch 182, and through plug 180 and receptacle 181 to the operating windings of receiving selecting relays 16 through 20, thereby causing the operation of these relays in accordance with the signals sent from the transmitter 170.

It will be understood of course that the receiving multiplex distributor of Fig. 1 is in this instance disconnected so that ground is not supplied through its segments to any of the selecting relays 16 through 20. In effect, therefore, the transmitter 170 and test distributor is substituted for the receiving multiplex distributor and signals from the transmitter 170 are sent through the repeater to the distant terminal station. At the same time, due to the setting of the switch 182 and the insertion of plug 177 in receptacle 178 of the repeater operating in the opposite direction, signals which are received through that repeater are impressed upon the printer selecting magnets 176 thereby making it possible to receive signals from the same distant terminal station to which signals are being transmitted.

It will be clear by reference to Figure 5 that the sixth pulse to the first repeater is supplied from the sixth pulse contacts of the sending side of the test distributor over the wiper arm of the sixth contact bank in the lower row, and thence over conductor 201 and through plug 180 and receptacle 181 to the operating winding of sixth pulse control relay 25 (Fig. 1), thus substituting the sixth pulse contacts of the test distributor for the sixth pulse contacts 24 of the multiplex receiving distributor.

It will likewise be clear that the sixth pulse for the sixth pulse magnet 176 of the monitor printer is supplied from contacts B of stepping magnet 88 in the same manner as has been described above in connection with monitoring on the sending side of the repeater.

When the monitoring switch 182 is set in its fifth position, circuits are set up for testing a single multiplex channel repeater. In this instance signals from the transmitter 170 are substituted for signals from the receiving distributor of Figure 1 in exactly the same manner as was described above in connection with "talking" over the repeater. However, instead of plugging plug 177 into the receptacle 178 of the repeater operating in the opposite direction, it is plugged into the receptacle of the same repeater. Therefore the signals received on the monitor printer are the same signals which are passing to the line and should be, if the repeater is operating properly, the signals which were supplied to the repeater from the transmitter 170. Since the circuits are identical to those just described in connection with "talking," with the exception that the plug 177 is inserted in the receptacle 178 of the same repeater, and with the exception that the sixth pulse from the sending segments of the test distributor is supplied not only to relay 25 as in "talking" but also to sending sixth pulse relay 81 (Fig. 2), these circuits will not be traced again.

It will be noted that the transmitter 170 of the monitoring set is supplied with a jack similar to that of the transmitter of Figure 3. This is supplied in order that the speed reduction unit of Figure 3 may be utilized with the monitoring set for "talking" since, as will be obvious, the effective signal speed must be reduced in some instances and it is simpler to reduce it with the aid of this unit than to readjust the test distributor.

While I have described a preferred embodiment of my invention, and have described various elements of my invention in combination with various other elements, it will be understood that other forms of the invention may be utilized, and that some elements might be utilized without utilizing all. Therefore it is understood that the scope of the invention is not to be limited by the foregoing specification, but is, on the other hand, to be limited solely by the appended claims.

What is claimed is:

1. In a repeater for repeating signals from a channel of a multiplex receiving distributor associated with one line section and operating at a relatively low effective signal speed, to a channel of a multiplex sending distributor associated with another line section and operating at a relatively high effective signal speed, in combination, means for receiving character signals from said receiving distributor, a group of signal storing means, means for transferring successively received character signals to successive ones of said group of storage means, means for preventing the transmission of received ineffective signals to said storage means, means for transferring said stored effective character signals to the multiplex sending distributor of the second line section at a rate dependent upon the speed of said sending distributor, and means under the joint control of said two transferring means to cause said first mentioned transferring means to operate twice in rapid succession whenever said second transferring means lags said first transferring means by a single step of movement.

2. In a device for repeating signals from a channel of a multiplex circuit operating at a particular effective signal speed to a channel of another multiplex circuit operating at the same effective signal speed but a different over-all sig-

nal speed, in combination, means for receiving effective and ineffective code impulse signals from the first multiplex circuit, a plurality of groups of means for storing said code signals, means for transferring effective code impulse signals from said receiving means to successive groups of storing means, said transferring means comprising a rotary switch and means to operate the latter through one step of movement upon reception of each effective code signal, means for sending code impulse signals to said second multiplex circuit, and means for transferring signals successively from said groups of storage means to said sending means, said transfer means comprising a second rotary switch operable step by step at a rate determined by the over-all speed of said sending means, and means under the joint control of said first and second rotary switches to cause said first switch to perform two stepping operations whenever said second switch attains a position one step behind said first switch, said double stepping operation serving to insert ineffective signals into the train of effective signals sent from said sending means, to thereby render the over-all rate of sending 25 equal to the predetermined over-all speed of said signal sending means.

3. In a multiplex telegraph circuit including a repeater for repeating signals from a channel of a first line section to a channel of a second line section operating at an over-all signal speed less than that of said first line section, means for reducing the effective signal speed on said first line section to a speed less than the over-all signal speed of said second line section, said means comprising in conjunction with a multiplex tape transmitter a rotary switch operable step by step under control of the transmitter operating pulse, and means under control of said rotary switch for periodically preventing operation of said tape transmitter whereby idle signals are sent over the first line section thereby reducing the effective signal speed to a point less than the over-all signal speed of the second line section, and means in said repeater for periodically inserting idle signals sufficient in number to bring the over-all speed of transmission on the second line section to the normal operating speed of that line section.

4. In a speed reducing unit for reducing the effective signal speed of a multiplex transmitter, in combination, a rotary switch of the step by step type, means to operate said switch upon reception of each transmitter impulse, and connections through certain of the contacts of the wiper of said switch to the locking mechanism of said transmitter to cause periodic operation of said locking mechanism whereby said transmitter periodically sends a blank signal.

5. In a speed reducing unit for reducing the effective signal speed of a multiplex transmitter, in combination, a rotary switch of the step by step type, means to operate said switch upon reception of each transmitter impulse, a manually settable switch, connections through said switch to the contacts of said rotary switch, and a circuit leading from the wiper of said switch to the locking mechanism of said transmitter to cause periodic operation of said locking mechanism at intervals dependent upon the setting of 70 said manually settable switch.

6. In a multiplex channel repeater of the type described, means for receiving multiple impulse code signals from one line section, means for storing a limited number of said signals, means

5 for transmitting said signals to a second line section and indicating means operable when signals are received more rapidly than transmitted during a period sufficient to exceed the storage capacity of said storing means.

7. In a multiplex channel repeater of the type described, signal receiving means, signal storing means, a receiving rotary switch for transferring signals from said receiving means to said storing means, signal transmitting means, a sending rotary switch for transferring signals from said storage means to said transmitting means, means for causing said receiving and sending rotary switches to maintain a relationship within predetermined limits such that said sending switch normally lags said receiving switch by at least one step of movement but not by the number of steps of movement comprising a complete rotation, and means operable when said receiving switch comes into phase with said sending switch to operate an alarm signal.

8. In a multiplex channel repeater adapted to repeat signals from a receiving multiplex distributor to a sending multiplex distributor operating at a different speed, in combination, signal impulse receiving means, a control relay operable under control of the receiving distributor, means to prevent operation of said relay unless one or more of said signal receiving means have operated, means controlled by said control relay for locking said signal receiving relays in operated position, signal storing means, a rotary receiving switch normally connected to contacts of said control relay through contacts of said 30 receiving relays to transfer signals to said storage means in accordance with the signals received, transmitting means, a rotary switch for connecting said storage means with said transmitting means, a signalling means, and means comprising a relay shunted around the contacts of said control relay and normally deenergized for indicating when said two rotary switches are in phase due to said first switch operating more rapidly than said second switch for operating said signalling device.

9. A multiplex channel repeater comprising means for receiving signals from one line section, means for transmitting signals to another line section, means for storing signals, means for transferring signals from said receiving means to said storing means, means for transferring signals from said storing means to said sending means, means for operating said two transferring means at different instantaneous rates, said second transferring means normally operating more rapidly than said first transferring means, and means operable when said first transferring means overtakes and is in phase with said second transferring means for indicating such abnormal condition.

10. In a multiplex channel repeater, in combination, means comprising a group of relays for receiving multi-impulse code signals, a plurality of groups of signal storage means, means for connecting said receiving relays to successive groups of said storing means, a control relay operating repeatedly at a predetermined rate to actuate said signal storing means connected with operated receiving relays, signal transmitting relays, means for connecting said signal transmitting relays to successive groups of said signal storing means at a different and normally equal rate to the connection of said signal receiving means, said two connecting means being normally out of phase with the first leading the

second, an indicating relay and a circuit completed from said control relay over said receiving relays and said two connecting means to said sending relays when said first connecting means reduces the lead of said second connecting means to zero, said completed circuit effectively removing a shunt from the winding of said indicating relay, said relay thereby operating to give an indication of the abnormal in phase relationship of the said two connecting means.

11. In a multiplex channel repeater, in combination, means comprising a group of relays for receiving multi-impulse code signals, a plurality of groups of signal storage means, means for connecting said receiving relays to successive groups of said storing means, a control relay operating repeatedly at a predetermined rate to actuate said signal storing means connected with operated receiving relays, signal transmitting relays, means for connecting said signal transmitting relays to successive groups of said signal storing means at a different and normally equal rate to the connection of said signal receiving means, said two connecting means being normally out of phase with the first leading the second, a lamp for indicating an off speed condition, a relay for operating said lamp, and a circuit completed from said control relay over said receiving relays and said two connecting means to said sending relays when said first connecting means reduces the lead of said second connecting means to zero, said completed circuit effectively removing a shunt from the winding of said indicating relay, said relay thereby operating and lighting said lamp to indicate the off speed condition.

12. In a multiplex channel repeater adapted to repeat signals from a receiving multiplex distributor to a sending multiplex distributor operating at a higher effective signal speed, in combination, signal impulse receiving relays, a control relay repeatedly operable under control of the receiving distributor at a rate equal to the effective signal speed, a plurality of groups of signal storing means, means for connecting said groups of signal storing means successively to said signal receiving relays, said control relay having a contact for supplying current to said signal receiving means to thereby effect transfer of received signals to said storing means at a rate equal to the effective signal speed of the receiving distributor, signal impulse sending relays, means to connect said sending relays successively to said groups of storage relays at a rate determined by the sending distributor speed,

and an alarm signal operable under control of said control relay when the effective signal speed of reception exceeds the speed of transmission.

13. In combination with a pair of channel repeaters of the type described, and interconnecting two multiplex circuits for repeating in both directions, means for stopping transmission from one of said repeaters, and means under control of said stopping means for causing said second repeater to transmit stop signals back over the line.

14. In combination with a pair of channel repeaters of the type described interconnecting channels of two multiplex circuits for repeating messages in both directions, means comprising a manually operable switch and a slow releasing relay at each repeater for stopping transmission from that repeater, a relay at each said repeater connected through contacts of said slow releasing relay to the corresponding relay of the other repeater when said slow releasing relay is operated, and to ground when said slow releasing relay is released, and means operated by said second relay at each repeater for causing that repeater to repeatedly send a stop signal over its outgoing multiplex channel.

15. In a multiplex channel repeater, in combination, means for receiving signals over a multiplex channel at a predetermined speed, means for locking and subsequently releasing said receiving means, means for storing said signals, means for sending stored signals to another multiplex channel at a different predetermined speed, and means for monitoring the received signals, said means comprising a multiplex printer having its selecting magnets connected in parallel with said means for receiving signals, and means for breaking all said parallel circuits simultaneously to prevent the inductance of said printer magnets from preventing release of said repeater signal receiving means.

16. In a multiplex channel repeater, in combination, means for receiving signals over a multiplex channel at a predetermined speed, means for storing said signals, means for sending stored signals to another multiplex channel operating at a different channel speed, and means for monitoring the operation of said repeater, said means comprising a multiplex transmitter and a multiplex distributor connected to transmit signals to said repeater receiving means, and a multiplex printer adapted to receive signals from said repeater transmitting means.
